UNITED STATES PATENT OFFICE.

ALBERT A. KELLOGG, OF CLINTON, MISSOURI, ASSIGNOR OF ONE-HALF TO
GUSTAVE C. HAYSLER, OF CLINTON, MISSOURI:

END-GATE FASTENER.

SPECIFICATION forming part of Letters Patent No. 700,143, dated May 13, 1902.

Application filed March 14, 1902. Serial No. 98,200. (No model.)

To all whom it may concern:

Be it known that I, ALBERT A. KELLOGG, residing at Clinton, in the county of Henry and State of Missouri, have invented certain 5 new and useful Improvements in End-Gate Fasteners, of which the following is a specification.

My invention relates to that type of end-gate fasteners in which locking means, including a rod or bar adapted to extend transversely over the end-gate, and devices connected to the wagon-body for coöperating with the opposite ends of said bar or rod for effecting a pull strain on the opposite sides 15 against the ends of the end-gate; and my said invention primarily seeks to provide a very simple, economical, and easily-manipulated end-gate fastener means of the character noted capable of being readily applied to its locking or unlocking position without the necessity of unscrewing nuts, bolts, &c., and which will effectively serve for its intended purposes.

In its generic nature my invention comprehends a novel construction of hinge member for engaging with the outer end of one of the wagon sides, a bar or rod, one end of which is adapted to connect with the hinge-bar, and a special construction of lock devices for engaging the other end of the said bar, the several parts having a peculiar correlative arrangement and combination of parts, all of which will hereinafter be fully described, and specifically pointed out in the appended 35 claims, reference being had to the accompanying drawings, in which—

Figure 1 is a perspective view of a portion of a wagon-body equipped with my improved end-gate fastener, the end-gate being shown 40 fastened. Fig. 2 is a horizontal section of the same, the fastener devices being shown unlocked to permit of the removal of the end-gate. Fig. 3 is a perspective view illustrating the locking devices loosened to permit 45 the gate member being raised. Fig. 4 is a perspective view of the lock-bar holding or clamping means hereinafter referred to.

In the accompanying drawings, in which like characters indicate like parts in all of the figures, 1 designates the wagon-body, which may be of any approved construction, and 2

the end-gate, preferably made of plain boards, having the usual bracing - cleats 2^a 2^b, as shown. At one side the wagon-body has the usual pair of vertical cleats or guides 3 3 to 55 receive one end of the end-gate 2, and at the opposite side the vertical or side portion 1^a of the wagon-body terminates in a plane with the outer surfaces of the end-gate 2 when the same is adjusted to an operative position, and 60 the said side 1^a has a single bearing-cleat 4 to receive the end 2^x of the end-gate 2, as clearly shown in Fig. 1. Upon the outer end of the side member 1^a is hinged a swinging cleat 6, preferably a wooden member, secured 65 to the member 1^a by the strap-hinges 5 and in such manner as to close flatwise over the end of the wagon portion 1^a 1^a and to lie in a plane with the cleats 2^a of the end-gate. (See Fig. 1.) The member 6 is of such length 70 that its inner end 6^a will project beyond the inner edge 1^x of the wagon-body portion 1^a, and the said projecting portion 6^a forms, as it were, a cleat portion for coöperating with the cleat 4 to form a proper guide for the end 75 2^x of the end-gate 2.

So far as described it will be noticed that when the hinged cleat 6 is swung outward to the position shown in Fig. 2 the end-gate 2 can be readily detached from the wagon-body by 80 swinging it outward in a horizontal plane, as indicated by the arrow *a* in Fig. 2, and it can be likewise fitted in position and securely held in place by turning the hinge member 6^a over to the position shown in Fig. 1 and locking 85 the same to said position. As a simple and inexpensive means for holding the hinged member 6 to its closed position I provide the same with an eye or hook 6^b, adapted to receive the hook end 7^a of a locking-rod 7, adapted 90 to extend over the outer face of the end-gate and to connect with a locking device 8, the peculiar construction of which is best illustrated in Fig. 4, by reference to which it will be seen the same consists of a vertically-disposed rock-shaft 8^a, having a crank member 8^b, with which the end 7^c of the rod 7 pivotally joins, and provided with a handle portion 8^c. 95

To maintain the rod 7 in a proper position 100 and from accidental displacement, the end 1^y of the member 1^a of the wagon-body and

the adjacent cleat 3 are slotted horizontally, as indicated by x , to receive the lock-engaging end of the rod 7. By providing the slot x and arranging the rod 7 to coöperate therewith in the manner shown and described when drawn to its locked position the said rod 7 will be caused to lie snugly against the cleats 2^a of the end-gate, and thereby hold the said gate firmly pressed against the inner cleats 3 and 4 from rattling and from accidental displacement.

- By providing a locking member having a crank portion 8^b joined to the end 7^c of the rod 7 it is manifest that when the crank-shaft 8^a is adjusted to the position shown in Figs. 1 and 4 the pull strain on the rod 7 will serve to maintain the locking device 8 to its adjusted and locked position. Furthermore, by connecting the rod 7 with the hinged cleat 6 20 and with the locking device 8, as stated, the said rod 7 and the hinged cleat 6 can be sufficiently loosened to permit of raising the end-gate or removing it vertically, if desired, without detaching the rod 7 from the member 6. 25 By disconnecting the hook end 7^a of the rod 7 from the eye 6^b the hinge-cleat 6 can be readily swung out and the end-gate removed by pushing it out in a horizontal direction, as before stated. 30 From the foregoing description, taken in connection with the accompanying drawings, it is thought the advantages of my invention will be readily understood. The same is of a very simple and economical construction 35 and can be readily adapted for any of the ordinary types of wagon-bodies.

Having thus described my invention, what I claim, and desire to secure by Letters Patent, is—

- 40 1. In an end-gate fastening means of the character described, the combination with the wagon side, one of the said sides having the ordinary fixed end guide-cleats, the other

side having its end terminating in a plane with the outer face of the end-gate, and provided with a single fixedly-held inner cleat member; of the member 6 hinged to the outer edge of the wagon side, having the fixed cleat, and adapted to swing inwardly and beyond the inner face of the wagon-body side to 50 which it is hinged, to form a guide portion for coöperating with the fixed cleat, the end-gate section having the stay portion 2^a, the rod 7, detachably connected at one end to the hinged member 6, adapted to extend across 55 the end-gate and to bear against its cleats 2^a, and means on the wagon-body for drawing the said rod to a locking position, said means including a crank-shaft, adapted to be automatically held to its locked position by the 60 strain on the rod 7, substantially as shown and described.

2. The combination with the wagon-body sides 1^a 1^b, the cleats 3 3, fixedly secured to the side 1, the outer end of the side 1 and 65 the cleats 3, being slotted horizontally, the fixed cleat 4, secured to the side 1^a, and the end-gate 2; of the member 6 hinged to the end of the side member 1^a, to close inward over the end of the said side member, and to 70 project inwardly beyond the inner side of the member 1^a to form a cleat portion to coöperate with the fixed cleat 4, the rod 7, one end of which is adapted to play in the slot formed in the members 1 and 3, said rod 7 having a 75 hook portion 7^a, adapted to detachably engage with the member 6, and the crank-shaft 8, having a pivotal engagement with the rod 7, and provided with a handle member for adjusting it, all being arranged substantially 80 as shown and for the purposes described.

ALBERT A. KELLOGG.
